CLAIM

The ornamental design for a diagnostic apparatus as shown
and described.

DESCRIPTION

The patent or application file contains at least one drawing
executed in color. Copies of this patent or patent application
publication with color drawings will be provided by the
Office upon request and payment of the necessary fee.

FIG. 1 is a front perspective view of the diagnostic
apparatus according to our design;

FIG. 2 is a rear perspective view thereof;

FIG. 3 is a front view thereof;

FIG. 4 is a rear view thereof;

FIG. 5 is a bottom view thereof;

FIG. 6 is a top view thereof;

FIG. 7 is a right-side view thereof, the left-side view being
a mirror image thereof; and,

FIG. 8 is a bottom perspective view thereof.

The blurred sections in the drawings in FIGS. 1-8 are
intended to show portions of the article and their boundaries
that form no part of the claimed design.
